HAIR WAVE PROCESSING INDICATOR

Alfonsas Uselis, Brooklyn, N. Y.

Application February 1, 1955, Serial No. 485,569

9 Claims. (Cl. 73—160)

The purpose of the hair wave processing indicator is to provide an accurate mechanical means for measuring the length of time that, in each individual case, is necessary for a hair waving lotion used in permanent waving of hair to be allowed to remain on the head of hair before the application of a neutralizer. By the use of this instrument, it is possible to determine accurately, prior to the application of the hair waving lotion to a person's hair, the length of time necessary to obtain a soft, medium or hard wave, as may be desired.

It is known that the characteristics of each person's hair may differ in regard to the degree it will be affected by the action of the hair waving lotion. An individual using a hair waving lotion may find that the resistance of such individual's hair to the conditioning action of said lotion may be of long duration as compared to that of another individual. By the use of the hair wave processing indicator, it is possible without the use of test curls, and without guess work that may arise because of differences in the strength of the hair waving lotions, to obtain results far more precise than otherwise obtainable by measuring the degree of resistance of each individual's hair to the action of the particular hair waving lotion being used to condition the head of hair for a permanent wave.

The application of a hair waving lotion to a head of hair is to reduce it to a desired plastic state, or, in short, to condition or soften the hair for a permanent wave. The duration of the application of a hair waving lotion to a head of hair is of extreme importance; the duration of the application, which is critical, varies as to each head of hair and as to each hair waving lotion. Time is of the essence. If the application of a hair waving lotion to a head of hair is not timed accurately the permanent wave turns out to be over- or under-processed. The object of the hair wave processing indicator is to provide a novel hair testing apparatus for ascertaining the duration of the application of a hair waving lotion to a head of hair prior to the treatment of a head of hair for a permanent wave.

The problem confronting the beauty operator or the individual user of a hair waving lotion is the determination of the length of time of the application of the hair waving lotion to a head of hair before the application of the neutralizing solution. In the case of the beauty operator using the same hair waving lotion on the heads of hair of all the customers the problem of the beauty operator is to note the inherent differences in the structure of each customer's hair and to estimate haphazardly the duration of the application of the hair waving lotion. In the case of the individual user of a hair waving lotion at home, such individual attempts by the hit-and-miss method to discover the correct duration of the application of the hair waving lotion, and eventually finds the correct duration of the application but, in many cases, only after the expense of a number of purchases of the same hair waving lotion. If the beauty operator or the individual user

changes the brand of the hair waving lotion and begins the treatment for permanent wave using another brand of hair waving lotion the problems incident in its use repeat themselves.

5 By the use of the hair wave processing indicator, the beauty operator or the individual user of a hair waving lotion can discover the correct duration of the application of a hair waving lotion before the hair waving lotion is applied to a head of hair. The present invention is used 10 by the beauty operator or an individual user on a strand of hair from the head of hair to be given the permanent wave to determine the resistance of the hair to being softened or conditioned for a permanent wave by the action of the hair waving lotion. The clocking of the time, 15 that the action of the hair waving lotion requires to soften or to overcome the resistance of a strand of hair in its normal or natural condition and to transform a strand of hair from its normally straight or natural condition to a curled or wavy form, is an important and necessary step 20 in the use of the present invention.

The present invention provides a novel hair testing apparatus which includes a two-sectional interlocking and transparent case. The bottom section of the case for holding the hair waving lotion and the top section of the 25 case affixed with the operating elements to hold loosely the strand of hair being tested in position between the stationary comb and a rotative comb tensioned to such a degree as to depress the strand of hair in the openings of the stationary comb as the softening or conditioning action 30 of the hair waving lotion on the immersed strand of hair progresses. The time required for the rotative comb to depress fully the immersed strand of hair, or to transform said strand of hair from its normal or natural condition to a curled or wavy form determines the duration 35 of time of the application of the hair waving lotion on the head of hair before the application of the neutralizing solution. The present apparatus has an indicator dial to show when the resistance of the strand of hair to the softening or conditioning action of the hair waving lotion 40 has been overcome, or when the strand of hair has been transformed from its normal or natural state to a curled or wavy form.

The present invention has other and further objects 45 which will be apparent from the following description and claims and are illustrated in the accompanying drawings, which show a preferred embodiment of the invention, but other embodiments of the invention embodying the same principle may be used with modifications and changes without departing from the present invention.

Referring to the drawings, Fig. 1 is a side view, Fig. 3 is the other side view, Fig. 4 is a side elevational view of that portion of the apparatus below line *a—a* of Fig. 3 showing the shape and form of the teeth of the stationary and rotative combs in operative position, and Fig. 55 2 is the front view with a schematic diagram of the hair wave processing indicator showing all of the component parts.

The attached diagram of the hair wave processing indicator shows the constituent numbered parts as follows:

The dial 1 is calibrated in degrees of resistance of a strand of hair 16 to the softening or conditioning action of the hair waving lotion, showing at the extreme left side an R to designate full resistance, and O at the extreme 65 right to indicate the point at which resistance has been completely removed by the hair waving lotion action. Intervening dial markings within this range show progressively the degree of hair softening or conditioning starting from the R (resistance) side.

70 The apparatus is encased in a two-section, transparent case having a top section 12 and a bottom section 17. The bottom section 17 of the case, wherein the strand of

hair 16 being tested is immersed, is the container of the hair waving lotion.

The frame 3 with bottom, top and sides is set permanently on one side of the top section of the case 12 by means of two machine screws 8 and machine screw nuts 10. The frame 3 (with bottom, top and sides) has a revolving flat bar or shaft 18 extending from one side to the other side of the frame 3. On one end of the revolving bar or shaft 18 is a hand operable wheel or knob 11 and on the other end of the revolving bar or shaft 18 is an indicating arm 2 whose top end acts as pointer needle on the dial 1 located near the top of one side of the frame 3. A rotative comb 4 with depending teeth is affixed to the revolving bar or shaft 18, which is connected to a main spring 9 which at its correct tension represents the balancing measure of the degree of resistance exerted by the strand of hair. The main spring 9 is regulated and adjusted by a tension spring 7 which is attached to the top of the frame 3 and which is locked into correct position by means of an adjusting screw 14 and locking nut 13.

Near the bottom of the frame 3 and on each side thereof are grooves 15 and adjacent thereto are the hair holders 5 affixed to the inner surfaces of the sides of the frame 3. A stationary comb 6 with upstanding teeth is affixed to the bottom of the frame 3. The strand of hair 16 to be tested is placed between the teeth of the stationary comb 6 and the teeth of the rotative comb 4, into the hair holders 5 and grooves 15 so that the end portions of the strand of hair 16 extend a half-inch or so beyond the sides of the frame 3.

To use the apparatus, the bottom section of the case 17 is removed from the top section of the case 12 and is then filled with the hair waving lotion to such level that will cover the bottom portion of the frame 3 wherein the strand of hair 16 is positioned.

By the use of the hand operable wheel or knob 11, the teeth of the rotative comb 4 is drawn away from the teeth of the stationary comb 6, and the strand of hair 16, removed from the head of hair to be permanently waved, is inserted between and horizontally across the inner surfaces of the teeth of the stationary comb 6 and the rotative comb 4. The end portions of the strand of hair 16 are then fitted into the hair holders 5 and the grooves 15 on each side of the frame 3. The hair holders 5 and the grooves 15 are provided merely for holding loosely and in a horizontal position the strand of hair 16 which end portions are allowed to extend beyond the sides of the frame 3 a half-inch or so. The rotative comb 4 is then allowed to descend and rest upon the strand of hair 16 being tested for waveability.

The dial 1 at this point registers R or some point toward the center of the dial 1 dependent on the thickness of the hair being tested. With the apparatus in this readiness, the bottom side of the frame 3 wherein the strand of hair is inserted, is immersed into the hair waving lotion contained in the bottom section of the case 17 which should have enough hair waving lotion to cover the strand of hair 16. As the hair waving lotion begins its softening effect upon the strand of hair 16, the pressure of the rotative comb 4 upon the hair 16 begins to depress the hair 16 into the openings of the stationary comb 6, with such progressive softening being shown on the calibrations of the dial 1 by the indicating arm 2.

The length of time taken to reach an intermediate point of softening or complete softening is the determinant by which the desired result as to a soft wave, medium wave or hard wave is achieved when the hair waving lotion is subsequently applied to the hair of the person receiving a permanent wave. The length of hair provided for in the operation of the apparatus as above takes into account without distortion of results variations in thickness of hair growth over a span of many months.

The method based on the use of the hair wave processing indicator consists of the placing of one strand of hair

being tested in the apparatus and subjecting said hair to the softening or conditioning action of the hair waving lotion as described in the foregoing, with the design that the pressure of the rotative comb on the strand of hair as the strand of hair is being depressed into the openings of the stationary comb shall measure the degree of softness or plasticity attained in the said strand of hair or the degree of readiness of the strand of hair to waveability by the action of the hair waving lotion in which said strand of hair is immersed. By the uniform pressure applied on the length of hair in the hair wave processing indicator, no variations of results can occur due to the irregularities of thickness of the hair in normal growth from month to month. Specifically, this instrument provides the means for measuring, through readings obtained on the dial, the initial resistance of the hair being tested without the action of the hair waving lotion, and the progressive softening or conditioning of the hair resulting from the action of the hair waving lotion, thus enabling the operator to determine with full accuracy, by observing the dial and by clocking, the length of time to allow the particular hair waving lotion used to remain on the head of hair before the application of the neutralizing solution in order to achieve a hard, medium or soft wave, as may be desired, without the guesswork of test curls or other less accurate methods.

While the foregoing specifications set forth the apparatus of the invention in more or less specific terms, it should be understood that various changes may be made in the size, shape and kind of materials used in its construction, without departing from the spirit of the invention or the scope of the appended claims.

I claim:

1. In a hair wave processing indicator, useful for ascertaining the time necessary for the transformation of a strand of hair from a head of hair to be permanent waved, from its normal or natural state to a curly or wavy form or condition as it is immersed in a hair waving lotion to be applied to said head of hair, comprising, in combination, a case, said case having a top section and bottom section, said bottom section adapted to contain some of the hair waving lotion, a frame element with top, bottom and side members mounted and enclosed in the top section of said case, a dial means affixed to the top of the side of said frame, grooves on each side of said frame element adapted to hold opposite end portions of the strand of hair being tested, hair holders adjacent to said grooves and affixed to the inner surfaces of the side members of said frame, a revolving member extending between the sides of said frame, means for providing a predetermined and adjustable force to said revolving member, a rotative comb with depending teeth affixed to said revolving member, a stationary member with upstanding teeth affixed to the bottom of said frame, said upstanding and depending teeth being adapted to interleave with the test strand of hair therebetween whereby the strand of hair is depressed into the interstices of the teeth of said stationary member by the said means of force applied to the teeth of the said rotative comb as the chemical action of the hair waving lotion takes effect on the said strand of hair.

2. An apparatus as claimed in claim 1 in which the teeth of the said stationary comb and rotative comb are semi-circular cross-sectionally with the flat surfaces of the teeth of said stationary comb and rotative comb facing outwardly and the curved or round surfaces facing inwardly.

3. An apparatus as claimed in claim 1 in which the said stationary comb and rotative comb are adapted to interleave with the said test strand of hair.

4. An apparatus of claim 1 wherein the said main spring predetermined and adjusted by said tension spring is adapted to exert such force to said rotative comb as is necessary to depress the strand of hair through the interstices of the teeth of said stationary comb as the said

strand of hair is acted upon chemically by the hair waving lotion.

5. An apparatus as claimed in claim 1 in which the said revolving member is adapted to transmit the said means of force to the rotative comb.

6. An apparatus of claim 1 wherein the said revolving member is adapted to indicate the rotation of said revolving member.

7. An apparatus as claimed in claim 1, in which said dial means are designed to register the effect of the said means of force together with the chemical action on said strand of hair.

8. An apparatus as claimed in claim 1, wherein said hair holders and grooves position the strand of hair as it is inserted horizontally across the inner surfaces of the teeth of said stationary comb and rotative comb, and said hand operable wheel or knob designed to facilitate the insertion of the said strand of hair.

9. In a hair wave processing indicator, useful for ascertaining the time necessary for the transformation of a strand of hair, from a head of hair to be permanent waved, from its normal or natural state to a curly or wavy form or condition as it is immersed in a hair waving lotion to be applied to said head of hair, comprising, in combination, a case, said case having a top section and bottom section, said bottom section adapted to contain some of the hair waving lotion, a frame element with top, bottom and side members mounted and enclosed in the top section of said case, a dial means affixed to the upper portion of the side of the said frame element,

grooves on each side of said frame element adapted to hold opposite end portions of the strand of hair being tested, hair holders adjacent to said grooves and affixed to the inner surfaces of the side members of said frame element, a revolving bar or shaft extending between the sides of said frame element, a main spring affixed to said revolving bar or shaft, a tension spring connected to said main spring and affixed to the top of the frame element, said main spring and tension spring to provide a predetermined and adjustable force to the said revolving bar or shaft, a pointer or indicating arm connected to the said revolving bar or shaft and movable therewith across said dial, a rotative comb with depending teeth affixed to said revolving bar or shaft, a stationary comb with standing teeth and depending teeth being adapted to interleave with the test strand of hair therebetween whereby the strand of hair removed from a head of hair to be permanent waved is depressed into the interstices of the teeth of the said stationary comb by the means of force of said main spring and tension spring applied to the teeth of said rotative comb as the chemical action of the hair waving lotion takes effect on the said strand of hair.
